United States Patent Office

Des. 196,389
Patented Sept. 24, 1963

196,389

BOTTLE

Stanley I. Mason, Fullerton, Arnold Ehlis, Santa Ana, and Jay B. Mosby, Temple City, Calif., assignors to Hunt Foods and Industries, Inc., Fullerton, Calif., a corporation of Delaware

Filed Aug. 28, 1961, Ser. No. 66,526

Term of patent 14 years

(Cl. D58—8)

FIG. 1 is an elevational view of a bottle embodying our new design;

FIG. 2 is a top plan view thereof;

FIG. 3 is a bottom plan view thereof; and

FIG. 4 is a horizontal sectional view taken on the line 4—4 of FIG. 1.

We claim:

The ornamental design for a bottle, substantially as shown.
